No. 37,347.

Patented February 14, 1905.

UNITED STATES PATENT OFFICE.

CHARLES R. KNAPP, OF WINONA, MINNESOTA.

DESIGN FOR A SLEIGH.

SPECIFICATION forming part of Design No. 37,347, dated February 14, 1905.

Application filed March 7, 1904. Serial No. 197,050. Term of patent 14 years.

To all whom it may concern:

Be it known that I, CHARLES R. KNAPP, a citizen of the United States, residing at Winona, in the county of Winona and State of Minnesota, have invented a new, original, and ornamental Design for Sleighs, of which the following is a specification, reference being had to the accompanying drawings, forming part thereof.

Figure 1 is a perspective view of a sleigh of my new design. Fig. 2 is a rear end view thereof. Fig. 3 is a front end view thereof.

Having shown my invention, what I claim as new, and desire to have protected by Letters Patent, is—

The ornamental design for a sleigh, as shown.

CHARLES R. KNAPP.
